UNITED STATES PATENT OFFICE.

ALBERT C. FISCHER, OF CHICAGO, ILLINOIS.

EXPANSION-JOINT INSTALLER.

Application filed May 26, 1922. Serial No. 563,832.

Heretofore it has been the practice to install expansion joint in a manner which caused the installing apparatus to interfere with the contact between the joint and the concrete adjoining it.

My invention relates to an expansion joint installer which will not interfere with the contact of the concrete on the sides of the joint, and which will serve other purposes in the way of holding the joint rigid even though the most flexible expansion joint be used.

My invention is accomplished by equipping the usual backing board with attachments which enable the asphaltic slab to be placed on the backing board and held in place while being carried to the location where it is to be staked and held in place during succeeding operation of laying the concrete without buckling or danger of bending the joint, thus making it possible to install the most flexible joint in concrete roadways in a straight line across the road.

It has been heretofore proposed to use certain types of joint with reinforced sides that do not require the backing board, but this requires double staking on each side, thus weakening the concrete structure if the stakes are not removed. Likewise, a joint in the quarter inch size of this material is very flexible in hot weather, and extremely difficult to handle because of the effect of the heat on the asphaltic content of the joint.

Likewise, most installers make it necessary to insert the expansion joint between the sides or projections of the installer, thus making it difficult and inconvenient to install the joint. With my invention it is only necessary to transfer the slab or strip of asphalt from the crate to the backing board while lying flat, and laying over it the attachment of the backing board, which is fastened by hinges, making it more convenient to carry to the section which is to be provided with the expansion joint, and also making it easier to install by reason of the more rigid structure of the backing board.

My invention is new, original and simple, and accomplishes with speed what otherwise would require time and considerable labor, and which in actual practice has been found to be unsuccessful and impractical, with the results that after attempts to place them on the market they have met with failure.

The improvement in question will bring

to contractors and persons installing expansion joint the use of materials which heretofore could not be conveniently handled except at considerable expense, and this type of installer will enable them to install expansion joint at a low minimum cost and also purchase materials at a low cost, thus making for economy in concrete road construction, of considerable importance to the general public.

In order that my invention may be more fully described I will refer to the accompanying drawings in which Figure 1 is an elevational view of the installing device with the backing board in open position; Figure 2 is a perspective view of the backing board detached and equipped for service in molding asphalt joint; Figure 3 is a perspective view of a marginal strip adapted to be applied to the board of Figure 2 and forming a side wall of the mold; Figure 4 is a perspective view showing the installing device in position but without the joint-forming member; Figure 5 is a view similar to Figure 4 showing the joint-forming member in position and the backing member removed to expose the joint-forming member; Figure 6 is a view of the installing device as seen from the side opposite to that viewed in Figures 4 and 5, the joint-forming member being in position, and the backing board being folded thereon and in the act of forcing the joint-forming member upon the retaining pins. The reference character (a) represents the backing board, which is usually constructed out of wood, but any suitable material adapted for the purpose may be used. (b) represents the hinges attached to the backing board, and likewise attached to the bar (d). The hinges at (b) fold inwardly on the backing board, or may be provided to work in the opposite direction if it is so desired.

The bar (d) which is constructed either in the shape of a straight bar, parabolical curve or concave curve, depending upon the nature of the joint to be installed, is preferably made of a stiff rigid substance, as metal whether cast or otherwise, but may also be constructed of wood, or in fact any suitable substance which will answer the purpose.

(e) represents small projections which may be conical in shape with pointed ends, or which may be of uniform thickness in size, or otherwise constructed, their purpose

in this particular position being to imbed themselves in the asphaltic material which is placed upon the backing board (a).

The small projections or pegs may be of wood, metal or other materials suitable for the purpose, and it is generally understood that a contrivance may be used such as a continuous projection which would likewise imbed itself; or the bar may be made without any projections whatsoever, the mere pressure of the bar holding the asphaltic material in place.

(c) represents staking pins which are independent of the hinge action, and which are used to hold the backing board in place. They may be a part of the structure or may be constructed so as to be a separate unit of a structure and applied as an attachment, but the preferred form is that the entire structure should be so united together that there will be no possible loss of parts on the roadway. It can readily be understood that by attaching the crown of the pin (c) that they will place the installer in position without interfering in any way with any part of the structure.

It may be necessary when the installer is folded together that the backing board may have to be staked slightly on the opposite end to prevent it flaring open. This does not involve any particular trouble or labor.

Likewise, the pin (c) may be adjustable, and the bar (d) may likewise be adjustable, so that should the joint be of various sizes the installer will be adjustable by lowering or raising the bar (d). While such adjustment is not shown in the drawings it may be readily understood that a keyway or locking arrangement may be slit in the bar (d), or the hinge may be so equipped as to be slotted and permit of the raising and lowering of the bar (d) on its fastenings.

As a further convenience of this joint installer, the backing board (a) may be equipped as a mould, and enlarging upon this subject I refer to Figure 2, in which (a) represents the backing board, (g) a metal strip used as one of the outlines or confines of the mould, (h) representing little holes drilled in the backing board so that projections of the strip (g) may fit into the holes holding the strip in rigid condition in this manner.

A contractor can pour the asphaltic material while in a heated condition on the backing board, and would manufacture his own expansion joint and install it at the same time, by furnishing him with the proper asphaltic material and furnishing him adequate supplies and means with which to carry out this object with despatch and efficiency, thus greatly reducing the cost of installation to him.

It can readily be seen that by pouring asphaltic material in such a mould as shown

by Figure 2, by first soaping the backing board or using talc or any other suitable substance to keep the asphaltic material from adhering, that a strip of expansion joint could be readily cast on the ground while the concrete is being poured between expansion joints, it would be just as convenient for one individual to make four or five of these strips in cases where the joint would be used horizontally as well as transversely, and while the concrete was being poured in one section the asphaltic material would be cooling, so that the joint could be installed and ready by the time that the next section is ready for these strips. Of course, at the present time these strips are furnished in open market and are available to the contractor, but it requires packing, crating and the question of transportation is constantly encountered, the material often lying in the roadways many weeks before being used.

By enabling a contractor to prepare his own expansion joint on the job all this is eliminated, as he will receive his asphaltic material properly mixed in drums, and can use the same material on any job which he may have under contract. Likewise, a surplus of material will enable him to use it on other jobs, so that he will be able to buy his asphaltic material in large quantities and keep a continuous stock on hand, which may readily be used as required, or shipped to other jobs as needed.

After pouring the asphaltic material in the mould the strips (g) can readily be removed so that the slab of asphaltic expansion joint will lie in position, and all that is necessary is to fold the attachment over the backing board and install the joint in position.

Figure 3 illustrates a moulding strip, which is somewhat like that shown at (d) in Figure 1. This moulding strip may be of any design or pattern, but is preferably made so that it will be held in place level in order to obtain a uniform thickness of asphaltic material.

Figure 4 represents the expansion joint installer set up in front of the end of a day's pouring, illustrating the installer staked in the ground, showing the suspension bar (d) with its projections and the backing board (a) folded over and out of the way, in order that concrete may be poured upon the opposite side of the installer.

In Figure 5 we have this same view in the same position with the exception that the expansion joint (l) is mounted in place and suspended by the bar (d) on the projections (e) with the backing board (a) folded over. In this position the installer is ready to receive the concrete batch which is poured to a level of the bar, the protruding crown of the joint is thus pressed away from the projections and the installer pulled out by pull-

ing up the stakes. The removal of the stakes may be obviated by making stakes a separate unit, utilized with the installer so that the stakes may be left in the concrete batch if it is so desired. This would simply require the utilization of ordinary wooden stakes on either side of the installer holding the same in place until the concrete is poured on the side which the expansion joint faces, and having a fastening means between the bar and the stake, so that the bar will be held in position while the opposite side of the concrete mixture is poured.

In Figure 5, (b) represents the hinges, (d) the suspending bar, (l) slab of expansion joint, (e) represents the projections buried in the expansion joint and (c) the stake supports of the installer, (k) represents the concrete mixture put in place.

In Figure 6, (a) represents the backing board, (b) the hinges connecting the backing board and the attachment, (c) the stakes, (d) the supporting bar, (e) the projections on the supporting bar, (l) the strip of asphaltic expansion joint. This illustration shows how the attachment is folded over on the expansion joint with the supporting bar pressed against the upper edge of the joint, thus keeping it flat and in position for installation.

It may readily be understood that various types of construction may be utilized in bringing about the same results, and the stakes may be either a part joined with the installer as a whole or independently of the installer. Also the hinges themselves may be a part of the stakes, and other changes may be made which would not in any way affect the general plan of preparing an expansion joint for installation from a casting of the joint to its satisfactory installation in the pavement, or by using a premoulded joint which has already been prepared and laying same upon the backing board (a) in position for retention by support of the supporting bar (d) and the cross stake (c). It is also possible to fasten the backing board in some way to the stakes so that it will not be necessary to stake the opposite side of the backing board. However, it is preferable to eliminate all interference underground after the concrete has been poured, so that the stakes may be readily removed or the installer itself readily removed at time of installation.

One of the advantages of installing an expansion joint by my method is that a continuous joint can be cast and inserted; likewise strips can be laid butted or welded together and installed without allowing vacant spaces between joint ends, providing a continuous strip of expansion material between the concrete slabs.

In my application filed April 19, 1926, Serial No. 103,001, which is a division of the

present application, I am claiming the use of the equipment referred to in Figures 2 and 3 of this application as a moulding apparatus with which the joint may be installed on the job.

70

What I claim is:

1. Means for installing expansion joints in pavements, said means comprising a joint-suspending member, means for sustaining said suspending member in upright position, and means mounted on said sustaining member for engaging and holding one side only of an expansion joint strip while leaving the other side of the expansion joint strip presented free and unobstructed for contact with the paving material with which it is to be used.

75

2. Means for installing expansion joints in paving, comprising a suspending member, means mounted on said suspending member adapted to interengage with and support a paving joint strip upon said suspending member, said means being located to leave one surface of the paving joint strip exposed to receive paving material, and a backing member adapted to said exposed face of the paving joint strip but removable therefrom without releasing the paving joint strip from the suspending member.

80

3. Means for installing expansion joints for paving comprising a suspending member, impaling pins carried by said suspending member in position to imbed themselves in the paving joint strip applied to said suspending member, and means adapted to overlie the face of the paving joint strip and press the same into impaled relation to said pins; the last named means being removable from the paving joint strip independently of the suspending means.

95

4. Means for installing expansion joints, comprising a backing member adapted to receive a joint strip, and a suspending member movable to position over the strip on said backing member; said suspending member having means for engaging and supporting the strip when the backing member is moved away from the strip.

100

5. Means for installing expansion joints, comprising a backing member adapted to receive a joint strip, and a suspending member movable to position over the strip on said backing member; said suspending member having means for engaging and supporting the strip when the backing member is moved away from the strip; and said backing and suspending members being movably connected together to guide them in their movements to and from said strip.

115

6. An expansion joint installer consisting of a backing member, having hinges adapted to cooperate therewith, said hinges carrying a supporting member which may be folded upon the backing means and staking means attached to said supporting means.

120

125

130

7. Means for installing expansion joints, comprising a backing member adapted to receive a joint strip, and a suspending member movable to position over the strip on said backing member; said suspending member being provided with means for supporting it and the strip which it carries in an upright position upon the ground; said backing member being movable from the joint strip independently of said suspending member.
8. Means for installing expansion joints, comprising a backing member adapted to receive a joint strip, and a suspending member movable to position over the strip on said backing member; said suspending member being provided with stakes adapted to be driven into the ground; and said backing member being removable from the strip independently of said suspending member after the stakes are inserted.
9. The method of installing an expansion joint by providing expansion joint with a larger width than the width of the thick-
- ness of the concrete, placing said expansion joint material between the backing means and a supporting means, pressing the supporting means into the upper edge of the expansion joint material, thus suspending the expansion joint material between the supporting means and the backing means, later folding back the backing means and exposing the surface of the expansion joint material, the same remaining suspended upon the supporting means, and permitting the concrete to be poured about it, later removing the supporting means.
10. The method of installing expansion joint by heating the expansion joint material upon the job, casting same in an expansion joint installer, removing the moulding strips and properly staking the installer in position preparatory to the pouring of the concrete.

Signed at Chicago, Illinois, this 24th day 45 of May, A. D. 1922.

ALBERT C. FISCHER.
